UNDERGARMENT

John A. Boysen, Rutherford, N. J., assignor to
 Robert Reis & Co., New York, N. Y., a corpora-
 tion of New York

Application May 21, 1937, Serial No. 143,900

4 Claims. (Cl. 2—237)

The invention relates to undergarments and particularly to that type of men's undergarment known in the trade as "shorts."

Undergarments of this general type have heretofore been constructed with two front and two rear sections constituting the body of the garment with a fly opening in the front provided with buttons and cooperating button-holes, and in which a waistband of double ply has been secured to the upper edges of the garment sections by stitching along such edges. Such undergarments, by means of the fly opening at the front of the waistband, provide entry of the legs of the wearer into the leg portions of the garment.

In accordance with my invention, an undergarment for men's wear of the type known as "shorts" is constructed without buttons but with a continuous waistband provided in the rear portion of the garment with an elastic insert, the cloth of which the garment sections are constituted being cut in such a manner as to give a stretch of approximately 10 to 12 inches in the band so as to permit easy entry of the legs into the garment when the same is donned. In accordance with my invention, also, the fabric of the garment sections, instead of being secured at their upper peripheral edges to the waistband and to the elastic insert constituting one portion of such waistband, are continued upwardly so as to form an elongated piece, and the waistband, constituted of two overlapping plies, is placed over such elongated piece at the top of the sections so as to embrace the same which then will constitute a lining for the waistband.

A further object of my invention is to construct the waistband in such manner that instead of there being any stress or strain applied to the elastic portion of the garment, such stress or strain is applied substantially entirely at the point of each side of the band extending below the elastic insert. This is accomplished particularly by making the elastic insert of a less width than that of the waistband and particularly by cutting the material constituting the garment sections of large pieces and then gathering the upper edges of such garment sections to form a multiplicity of tufts along their upper edges.

A still further object of the invention is to provide an undergarment of this general type in which the pattern of the cloth is cut in such manner as to give an extra large leg portion to act as a lining for a man's trousers, thereby eliminating, when the garment is worn, friction between the undergarment and the body of the

wearer, and eliminating the possibility, so usual with the present type of undergarments of this character, of the leg portions of the undergarment riding up upon the leg of the wearer.

A particular embodiment of my invention is illustrated in the accompanying drawings in which Fig. 1 is a front view of an undergarment constructed in accordance with my invention; Fig. 2 is a rear view of the garment; Fig. 3 is a fragmentary detail of the region of the point of juncture of the waistband and elastic strip with the adjacent portion of the garment fabric proper; Fig. 4 is a view of the same region of the garment as that of Fig. 3 but from the rear, with a portion of the waistband cut away; Fig. 5 is a section on the line 5—5 of Fig. 1; and Fig. 6 is a section on the line 6—6 of Fig. 4.

Referring more particularly to the drawings, in which similar reference characters identify similar parts in the several views, the garment comprises assembled front and rear portions 7, 7 and 8, 8, respectively, joined vertically by seams 9, and seamed in the usual manner at their lower edges at 10. The two rear portions of the garment are joined by a seam 11.

Instead of providing the garment with the usual fly opening, one flap of which is provided with buttons, and the other with cooperating button-holes, my novel garment has a continuous, unopened waistband, and is provided with a fly opening in which one flap 12 is adapted to overlie the other, formed by the upper edge of the adjacent front portion 7 of the garment, the flap 12 being secured by stitching 13 near the lower extremity of the flap to the fabric edge constituting the under flap of the fly opening. The flap 12 is also secured to such fabric edge near the upper extremity of the garment portion by stitching 14. In this manner, a substantial closure of the fly is secured without the use of buttons or other closure means while giving the necessary opening to the fly structure when desired and returning the same to its closed position substantially automatically upon release of the flexing of the overlying flap 12.

The garment is provided with a waistband 15, constituted of the same linen or like material of which the body of the garment is made, such band, however, extending only substantially throughout the upper edge of the front sections 7, 7, the remainder of the waist-encircling element being constituted of an elastic strip 16, of less width than the band 15, the two being joined at their contiguous ends by stitching 17, 17.

In accordance with my invention, the front

sections 7, 7 extend (as shown in Fig. 5) beyond the lower edge 18 of the waistband 15 and substantially to the upper edge 19 thereof, the waistband, constituted of two overlapped sections 20 and 21, embracing between them, the upper portion of the garment sections so as to have such upper portion, which is an elongated piece at the top of the body of the garment, constitute a lining for such waistband. As clearly shown in Fig. 5, the edges of the waistband are turned inwardly and secured to the garment material by stitching 22, 23. The lining strip is secured in place between the folded over sections of the waistband by stitching 24.

15 Referring now more particularly to Figs. 2 and 3, it will be noted that the band 15 is of greater width than the elastic strip 16, and that the upper edge of the rear section is gathered to a considerable extent so as to form a multiplicity of tufts 25, the end portions 26 constituting a reinforcing section at the edge 21 of the waistband extending below the elastic strip 16. This construction results in a distribution of the stresses and strains placed upon the garment when worn, in such manner that such stresses and strains, instead of being applied upon the elastic part of the garment, namely the elastic strip 16, are applied at points at each side of the waistband constituted by the portions 27 thereof.

30 Referring now to Figs. 4 and 6, it will be noted that the elastic insert 16 is secured to the overlapping sections of the waistband 15, which straddle the upper portion of the rear section 8 of the garment constituting a lining for the waistband, as hereinabove described, by stitching 17. The upper edge of the fabric of sections 8 is shirred, as at 28, throughout the extent thereof, being secured to the lower edge of the elastic strip 16 by a double row of stitching 29, 29.

40 In accordance with the novel structure of undergarment hereinabove described, I provide such an undergarment eliminating all buttons and button-holes and similar cooperating closure means both upon the body of the garment and 45 upon the waist-encircling band. The advantages of eliminating buttons or other types of fastening elements are too well known to require exposition.

50 My novel undergarment is also characterized by longer wearing qualities than similar garments, not constructed in accordance with my invention, in that the strains and stresses, to which the garment is subjected in wear and in donning the same, are distributed so as to be applied at 55 points peculiarly capable of withstanding such stresses and strains, namely at the regions at each side of the ends of the waistband, instead of on the weakest part of the garment, constituted by the elastic portion of the band.

60 Furthermore, the undergarment, as shown and described, with the cloth cut in such manner as to give a stretch of from 10 to 12 inches in the waistband, contributes, in great measure, to the facility with which the garment can be put on, 65 permitting easy entry of the legs of the wearer into the garment. The garment is likewise so constructed by providing an extra large cloth pattern for the leg portions that such leg portions are of sufficient width, providing ample space for 70 the wearer's legs without having the garment leg portions hug closely the legs of the wearer and upon movement of the wearer, cause a riding upwardly of the garment upon the legs, but causing it, rather, to stay in position as a virtual lining 75 for the trouser legs.

While I have described a specific embodiment of my invention, it is obvious that various modifications therein, particularly in the arrangement and configuration of the several elements, may be made without departing from my invention. 5

I claim:

1. In an undergarment of the type described, assembled front and rear sections, an independent waistband of substantial width, running substantially throughout the upper edges of the front sections, said waistband being formed of a single piece of material folded over so as to have a closed upper edge and depending overlapped portions embracing between them a substantial part of the upper free edge portions of the front sections, so that such upper edge portions constitute a complete lining of substantial width for the waistband, and an elastic strip of narrower width than said waistband, secured to the ends of said waistband by stitching, the composite waistband extending throughout the upper circumference of the garment, the upper edge portions of said rear sections and of the contiguous parts of the front sections being gathered so as to form a multiplicity of tufts, whereby in the area immediately 25 below the line of stitching joining the elastic to the non-elastic portion of the waistband, at which area the inelastic portion extends below the elastic portion, there is a point in the inelastic portion of the waistband which relieves the stresses 30 and strains which would otherwise be applied to the line of stitching joining the elastic and non-elastic portions of the waistband, thereby preventing the destruction of such line of stitching. 35

2. In an undergarment of the type described, assembled front and rear sections, an independent waistband section of substantial width, running substantially throughout the upper edges of the front sections, said waistband section being formed of a single piece of material folded over so as to have a closed upper edge and depending overlapped portions, and a second waistband section constituted solely of a strip of single thickness elastic fabric of a length extending from substantially one hip region to the other, when the garment is worn, secured to the ends of said first waistband section by stitching, the composite waistband extending throughout the upper circumference of the garment, the upper edge portions of said rear sections being gathered so 40 as to form a multiplicity of tufts, whereby in the area immediately below the line of juncture there is a point in the inelastic portion of the waistband which relieves the stresses and strains which would otherwise be applied to the line of stitching 45 joining the elastic and non-elastic portions of the waistband, thereby preventing the destruction of such line of stitching. 50

3. An undergarment as claimed in claim 2, having a fly opening extending from the lower edge 55 of the inelastic waistband portion downwardly, whereby no buttons or other securing means are necessarily applied to the garment. 60

4. In an undergarment of the type described, assembled front and rear sections, an independent waistband of substantial width, running substantially throughout the upper edges of the front sections, said waistband being formed of a single piece of material folded over so as to have a closed upper edge and depending overlapped portions and an elastic strip of narrower width than said waistband, secured to the ends of said waistband by stitching, the composite waistband extending throughout the upper circumference of the garment, the upper edge portions of said 70 75

5 rear sections and of the contiguous part of the front sections being gathered so as to form a multiplicity of tufts, whereby in the area immediately below the line of stitching joining the elastic to the non-elastic portion of the waistband, at which area the inelastic portion extends below the elastic portion, there is a point in the

inelastic portion of the waistband which relieves the stresses and strains which would otherwise be applied to the line of stitching joining the elastic and non-elastic portions of the waistband, thereby preventing the destruction of such line 5 of stitching.

JOHN A. BOYSEN.
